UNITED STATES PATENT OFFICE.

FRED W. LYLE, OF LYNN, MASSACHUSETTS, ASSIGNOR TO GENERAL ELECTRIC COMPANY, A CORPORATION OF NEW YORK.

VAPOR ELECTRIC DEVICE.

1,091,680.

Specification of Letters Patent. Patented Mar. 31, 1914.

Application filed October 11, 1911. Serial No. 654,007.

To all whom it may concern:

Be it known that I, FRED W. LYLE, a citizen of the United States, residing at Lynn, county of Essex, State of Massachusetts, have invented certain new and useful improvements in Vapor Electric Devices, of which the following is a specification.

My invention relates to vapor electric apparatus, such as mercury vapor lamps, reflectors, and the like.

In some cases when mercury vapor devices, which are arranged to start by tilting, are restarted immediately after an interruption of the arc, the contact of the relatively cool mercury with the heated glass will cause cracking and put the lamp out of service. This is particularly true of devices which are operated at a high temperature. For example, mercury lamps in which the arc is operated in an inner quartz envelop, which becomes highly heated, and thus heats the outer glass envelop in its vicinity, contact between the heated glass and the cooler mercury remote from the quartz envelop is apt to result in cracking. In accordance with my invention this difficulty is obviated by providing means for delaying the restarting of the mercury lamp, or other vapor electric device, after an interruption of service. This delay which need only be of a few seconds' duration allows the device to cool down sufficiently to avoid cracking of the glass.

In the accompanying drawings, Figures 1 to 4 inclusive illustrate diagrammatically various arrangements for delaying the restarting of the vapor electric devices.

The particular form of mercury vapor lamp 1 shown in Fig. 1 is illustrative only. My invention is not limited in application to this type of lamp. The lamp is provided with an unsealed inner quartz tube 2 in which an arc plays. The lamp is supported by a pivoted framework 3 which is suitably attached to the solenoid of the tilting magnet 4. The electrodes of the lamp are connected across conductors 5, 6 in the usual manner. The tilting magnet 4 is connected in shunt with the lamp and in series with a resistance 7. In shunt with the magnet 4 is a mercury thermostat 8, somewhat like a thermometer, the circuit being completed by conductors 9, 10 sealed in the ends of the tubes. The thermostat is surrounded by a

heater 11 which is included in circuit with 55 conductor 6 in series with the lamp.

When a suitable current is impressed across conductors 5, 6, the shunt magnet 4 will draw up its armature and start the lamp by tilting in the well understood manner. The flow of current through the lamp deenergizes the tilting magnet and allows the lamp to descend and operate in a normal position. The current passing through the heater 11 causes the mercury to expand and 65 complete the contact between wires 9 and 10. This contact short circuits the tilting magnet 4 when the heater and therefore also the lamp is at normal operating temperature. The short-circuiting action incidentally prevents 70 the magnet 4 from drawing up its armature a second time when the voltage across the mercury arc in the lamp rises during operation as is the case in a device of this particular kind. The chief function of this 75 short-circuiting action however is to prevent the magnet 4 from restarting the lamp immediately if it should be extinguished for any reason during its normal period of operation. The magnet 4 cannot receive sufficient current to draw up its armature until the thermostat 8 has cooled off sufficiently to permit the contact between wires 9 and 10. 80 to be broken by the contraction of the mercury column. This interval of time which 85 may be adjusted to only of few seconds' duration if desired permits the glass in the vicinity of the heated quartz tube 2 to cool sufficiently to avoid cracking when the relatively cool mercury flows over its surface 90 during the starting of the lamp.

Instead of employing a mercury thermostat, any other of the well known forms of thermostats may be used. Fig. 2 illustrates a thermostat 12 consisting of two strips of 95 metal of unequal coefficient of expansion, such as zinc and iron. The device shown in Fig. 2 is otherwise the same as that shown in Fig. 1.

Fig. 3 shows a magnetic cutout 13 which 100 operates to open a circuit or shunt magnet 4 when a lamp is taking current in the normal manner. In this arrangement a thermostat 8 short circuits a magnet 4 in the manner described in Fig. 1. After an interruption of the arc, the magnet 13 will re-establish a circuit of the tilting magnet but this will not operate to start the lamp until 105

the heater, and therefore also the lamp have cooled off to some extent.

Fig. 4 shows an arrangement in which a tilting magnet is provided with two windings, an upper shunt winding 14 and a lower series winding 15. When the current is impressed across conductors 5, 6 the lamp is started in the manner already described in Fig. 1 by the pull of shunt winding 14. 10 When current passes through the lamp, series winding 15 is energized and opposes the magnetic pull of winding 14 and thus returns and holds the lamp in its normal position. The winding 15 is in series with 15 the heater 11 which causes the short-circuiting of shunt winding 14 by the extension of the mercury column as already described. In case of an interruption of current flow through the lamp, the shunt winding can- 20 not tilt the lamp to restart the same until the short circuit around magnet 14 is broken by the cooling of the thermostat. Various other arrangements for introducing the desired delay in the restarting of a vapor de- 25 vice will suggest themselves, in the light of the modifications herein described.

What I claim as new and desire to secure by Letters Patent of the United States, is,—

1. The combination of a vapor electric 30 device having a liquid vaporizable cathode, means for tilting said device to start the same and a thermal device for rendering the tilting means inoperative while the temperature of said thermal device exceeds a 35 predetermined limit.

2. The combination of a vapor electric 40 device having a vaporizable metal cathode, an inclosing envelop subject to injury by sudden change of temperatures, means for tilting said device to start the same, and means for rendering said starting device inoper-

ative for a predetermined interval after cessation of operation to permit cooling of said envelop.

3. The combination of a vapor electric device, means for supplying energy thereto, means for tilting said device to start the same, and means for delaying the restarting of said device when the arc is interrupted after a period of operation. 45

4. The combination of a vapor electric apparatus, means for supplying current thereto, an electromagnetic device for tilting said device to start the same, and a thermostat connected in shunt to said electromagnetic device and adapted to short circuit said device while the temperature of the thermostat exceeds a predetermined value, to secure a time lag in the restarting of the apparatus. 55

5. The combination of a mercury arc lamp, a magnetic device having opposed windings, one being in shunt and the other in series therewith, the shunt winding acting to tilt said lamp, and a thermal device 65 in series with the lamp for short circuiting the shunt winding, said device having a predetermined time lag.

6. The combination of a mercury vapor arc lamp, having an open quartz envelop 70 surrounded by an outer-glass envelop subject to cracking, means for tilting said lamp to start the same and means for delaying restarting of said lamp for a predetermined period of time after an interruption of its 75 operation to permit cooling.

In witness whereof, I have hereunto set my hand this ninth day of October, 1911.

FRED W. LYLE.
